TELEGRAPHIC CODE TEACHER

Harold M. Herman, Chicago, Ill.

Application September 4, 1946; Serial No. 694,684

1 Claim. (Cl. 178—115)

1.

This invention appertains to an improved apparatus for self instruction in the art of telegraphic code reception and sending, and it has for its primary object to provide one which is comparatively simple in design, highly efficient in operation, and inexpensive to manufacture.

Experience gained by me in the practice of the telegraphic art has proven that the most practical and rapid method of learning, or teaching, code reception and sending, is by the use of 10 mediums which will impress the visual, audible, and tactile senses of a student, at one and the same time, and my invention is directed to that end; the triple stimuli thus employed providing the student with means to see, hear, and feel, the 15 code signals, and results in an appreciable shortening of the time of learning.

Generally, the apparatus is comprised in a current source, such as a low voltage battery; a main control switch; a telegraph key of a more or less conventional type; an electromagnet for actuating the key; an electric light source; a sounder, such as a buzzer or like oscillator; a movable element carrying the dot and dash characters, i. e., letters of the alphabet, numerals, and symbols, of either the American Morse or Continental codes; a prime mover for driving the movable element; means for regulating the speed of the prime mover; and an automatic switching device cooperative with the movable element for making and breaking the circuit on the light source, the sounder, and the electromagnet associated with the key, correspondingly for each of the code characters as they move past the same; the several instrumentalities being arranged in a convenient and compact assembly on a suitable support or base. The movable element may take the form of either a disc or a tape of an electrical insulating material and have the code characters formed by cutouts or raised impressions, or made separate therefrom and interchangeably mounted thereon. A housing is employed to enclose the movable element and is provided with a sight window through which legible characters, identifying respective code characters, are exposed to view. Thus, with the apparatus in operation, a student, with a hand properly positioned in relation to the key, will not only feel the movements of the latter as each of the code characters are accurately produced, but, at the same time, will both hear and see the dot and dash formations, as well as visually identifying the same by reference to the legible characters appearing at the aforesaid sight window.

With the foregoing and other objects and advantages in view, the invention resides in the cer-

2.

tain new and useful combination, construction, and arrangement of instrumentalities, parts, and circuits, as will be hereinafter more fully described, set forth in the appended claims, and illustrated in the accompanying drawings, wherein:

Figure 1 is a schematic view of a preferred embodiment of the apparatus, in accordance with my invention;

Figure 2 is a fragmentary, longitudinal, vertical section, taken through the line 2—2 on Figure 3, looking in the direction of the arrows, showing the code signal transmitting disc and the automatic circuit make and break switching device cooperative therewith;

Figure 3 is a vertical, side, elevational view;

Figure 4 is a fragmentary, transverse, vertical section, taken through the line 4—4 on Figure 5, looking in the direction of the arrows;

Figure 5 is a fragmentary, vertical, side elevation of the housing for the code signal transmitting element, and showing the sight window through which legible characters, identifying respective code characters, are exposed to view; and,

Figure 6 is a diagrammatical view of the electrical circuit connections of the several instrumentalities constituting the apparatus.

Referring to the drawings in detail, the improved apparatus, as it is exemplified therein, is comprised in a base 10 having a telegraph key 12; a main control switch 16; a buzzer 18; a lamp socket 20; and a circuit terminal block 24; mounted in spaced relation thereon; substantially as shown in Figure 1. An electromagnet 14 is also mounted on the base 10 beneath the forward end of the key 12, and the socket 20 is provided with an electric lamp 22.

Rising from the base 10, rearwardly of the foregoing instrumentalities, is a substantially circular casing 30 in which a code character transmitting disc 44 is housed and mounted for rotation on a shaft 46 arranged in driven connection with the rotor shaft of an electric motor M mounted on the rear side of the casing 30, by means of bolts or screws 42.

The transmitting disc 44 has its edge notched, as at 48, in representation of the dot and dash combinations forming code characters, i. e., letters, numerals, and/or symbols, and these notches, during the rotation of the disc, successively engage the movable contact arm 52 of a switching device 50, causing it to make and break contact with the fixed contact arm 56 of the latter; the movable contact arm 52 being normally held on open circuit by means of a coil spring 54. This

switching device 50 is housed within a part 32, which is offset from the lower side of the casing 30 to support the same in vertical position, to which end it is provided with laterally extending ears 34 that are apertured to receive bolts or the like 40 for its securing to the base 10. The front wall 36, of the casing 30, is removable, it being normally held in place by means of screws 38.

The circuit terminal block 24 is provided with pairs of interconnected terminal posts 24a, 24b, and 24c, 24d; a battery 58 being connected across the posts 24a and 24c, while a conductor 60 connects the post 24b direct with one terminal of the motor M, and a conductor 62, the post 24d, through a rheostat 64, to the remaining terminal of the motor; the rheostat being provided to permit of the regulation of the speed of the motor and, consequently, that of the code transmitting disc 44. Other circuit connections are as follows: A conductor 66 connects the post 24b, of the terminal block 24, to one side of the main control switch 16, and a conductor 68, the opposite side of the latter, with a terminal of the electromagnet 14, which terminal, in turn, is connected by a conductor 70 to a terminal of the telegraph key 12. A conductor 72 connects the other terminal of the key 12 to a terminal of the buzzer 18 and a conductor 74 the remaining terminal of the latter to a terminal of the lamp socket 20, while a conductor 76 connects the other terminal of the lamp socket to the fixed contact 56, of the switching device 50. A conductor 78 branches off from the conductor 76 and connects with the remaining terminal of the electromagnet 14, while a conductor 80 extends from the post 24d, of the terminal block 24, and connects with the movable contact arm 52, of the switching device 50.

In the use of the code practice set as thus provided, and with the battery 58 connected to the terminal block 24 as stated, the motor M will start up and have its speed regulated by manipulation of the rheostat 64. With the starting up of the motor M, the code transmitting disc 44 will be rotated relatively to the movable contact arm 52, of the switching device 50, and the portions of its edge, between the notches 48, will successively exert a cam-like action on that contact arm and cause it to make and break the circuit at the fixed contact arm 56. By now closing the main control switch 16, with each closing of the circuit at the contact arms 52, 56, of the switching device 50, current will flow from the battery 58, by way of the posts 24a, 24b, conductor 66, the main control switch 16, the conductor 68, to one terminal of the electromagnet 14, where it divides, with a part passing through the electromagnet coils to the other terminal thereof and the other part passing, by way of the conductor 70 to the terminals of the telegraph key 12 and, from thence, by way of the conductor 72, the terminals of the buzzer 18, the lamp socket 20, and the conductor 76, to the fixed contact arm 56, of the switching device 50. From the said other terminal of the electromagnet 14, the divided part of the current, passing through the coils, flows by way of the conductor 78 to the point of the connection of the same with the conductor 76 and by the latter to the fixed contact arm 56, of the switching device 50. From the fixed contact arm 56, the current returns to the battery 58, by way of the movable contact arm 52, the conductor 80, and the terminal posts 24d, 24c, of the terminal block 24.

With the apparatus operating in this manner, the telegraph key 12, the buzzer 18, and the lamp 22, will be simultaneously energized by each impulse of current flowing through the circuit connecting these instrumentalities with the switching device 50 and the battery 58, so that a student will both hear and see the code signals transmitted from the latter when it is actuated by the disc 44, due to the sound emitted by the buzzer

10 and the flicker of the lamp. Also, by gripping the key 12 in an approved manner, the student will quickly learn the "feel" of the movements thereof in the forming of the dots and dashes of the code characters, as well as the pauses or intervals between the same, the duration of which being governed by the speed of rotation of the disc 44, as regulated from the rheostat 64. Additionally, the code characters formed on, or carried by, the disc 44, may be visually identified by the placing alongside of the same the corresponding legible characters, i. e., letters, numerals, and/or symbols, for exposure through a sight window 82, provided in the removable front wall 36, of the casing 30, substantially as shown in Figures 3 through 5.

15 In lieu of the buzzer 18, an audio oscillator (not shown), with headphone (not shown) may be employed to advantage, since it gives a good signal without making any noise to be heard by other than the recipient and also produces a tone more closely simulating actual (radio) signals.

20 30 Having thus fully described a practical and preferred embodiment of my invention, it is to be understood that the words which I have used are words of description rather than of limitation, and that changes within the purview of the appended claim may be made without departing from the true scope and spirit of my invention in its broader aspects.

What I claim is:

40 45 50 55 60 A telegraphic code teaching apparatus, comprising a base, a casing mounted in an upright position on the base, a horizontal shaft rotatably mounted in the casing, a disk fixed to the shaft and provided on its periphery with code characters, an electric motor fixed to the casing against one side thereof, gear means establishing a driving connection between the armature shaft of the motor and said first shaft, a telegraph key mounted upon the base at the opposite side of the casing, a part of said key constituting an armature, electro-magnets fixed to the base below the armature, switch means located within the base below the disk having a fixed contact and a pivoted contact, a spring normally holding the movable contact out of engagement with the fixed contact, an arm on the pivoted contact positioned for contact by the code characters of the disk, said characters and spring constituting means ultimately opening and closing the switch, conductors connecting the contacts with the electromagnet and with the current source.
